UNITED STATES PATENT OFFICE.

ELBERT O. HASKINS, OF RUTHERFORD, NEW JERSEY.

SECTIONAL HEATING-BOILER.

SPECIFICATION forming part of Letters Patent No. 707,229, dated August 19, 1902.

Application filed November 1, 1901. Serial No. 80,795. (No model.)

To all whom it may concern:

Be it known that I, ELBERT O. HASKINS, a citizen of the United States, and a resident of Rutherford, in the county of Bergen and State of New Jersey, have invented certain new and useful Improvements in Sectional Heating-Boilers, of which the following is a specification.

This invention relates to improvements in sectional heating-boilers, and especially to that class of boilers in which the several sections are brought in communication with each other by means of push-nipples. In boilers of this kind it has not been possible to cut out any one section—that is, to interrupt its communication with other sections in case this one section sprung a leak or was damaged in any other way, and thus the entire boiler had to be put out of service, causing great inconvenience and loss of time and money.

The object of my invention is to provide a new and improved sectional boiler in which the sections are connected by push-nipples and in which the above defect is avoided in a simple, reliable, cheap, and convenient manner.

In the accompanying drawings, in which like letters of reference indicate like parts in all the figures, Figure 1 is a vertical longitudinal sectional view of the upper part of one section of my improved boiler. Fig. 2 is a vertical transverse sectional view of the same. Fig. 3 is a view similar to Fig. 1, showing a modification. Fig. 4 is a vertical transverse sectional view through a series of sections, showing the construction of Fig. 3.

The cast-iron boiler-sections A, which may have any desired cross-section or shape, are provided at the top (and also at each side at the bottom in the usual way) with a slightly-tapering opening B in each face for receiving the ends of push-nipples C for bringing the several sections in communication with each other in the well-known manner, so that the water and steam can readily pass from one section into another, and thus the proper circulation of water maintained in the boiler. In my improved section the said openings B in each section A are surrounded by a partition D, extending from one wall a of the section to the other wall a, and thus forming a

chamber or compartment into and through which the circulating water or steam must pass in passing from one section to the other, 55 and this partition has an opening or openings through which the water and steam can pass into and out of the said section.

As shown in Fig. 1, the partition D is made cylindrical and is located some distance below the top of the section and is provided in its top with an opening E, which is preferably screw-threaded and provided with an external neck F, so as to give it greater depth. Above such opening the section has the usual 65 screw-threaded opening G, which can be closed by a plug H or into which a riser-pipe is screwed. Similar openings and plugs are provided at the lower ends of the legs of the section. In case a section A is to be cut out 70 for any reason whatever the plugs H are removed and a plug is screwed into the opening E of each partition D in the section and the plugs H are replaced. No water or steam can now pass into this section; but the communication between the other sections is not interfered with, as steam or water can pass through the space bounded by the partition D in the section cut out from the two sections at each side of the one that has been cut out. 80

In the construction shown in Figs. 3 and 4 the partition D' is made substantially semi-tubular, and part of the edge wall of the section A forms the balance of the compartment thus formed. 85

An opening J is formed in the bottom of the partition D' and an opening K at each side, and these can be closed by the screw-plugs L and M, respectively, when the section is to be cut out, the result being the same as when 90 the tubular partition D is provided.

Having described my invention, what I claim as new, and desire to secure by Letters Patent, is—

In a heating-boiler, the combination with a 95 series of sections provided with openings in their faces for establishing communication with adjacent sections, push-nipples inserted in said openings and a partition within each section, forming a compartment around said 100 openings and push-nipples, and extending from one wall to the other of said section, and made integral therewith, this partition having an opening for establishing communica-

cation between the compartment formed by said partition and the interior of the section within which said compartment is formed, said sections each having an opening in the 5 edge wall adjacent to the opening in said partition, substantially as set forth.

Signed at New York city, in the county of

New York and State of New York, this 16th day of October, A. D. 1901.

ELBERT O. HASKINS.
